John Mank

UNITED STATES PATENT OFFICE

BENJAMIN J. COHEN, OF NEW YORK, N. Y., ASSIGNOR TO D. KALTMAN & CO. INC., OF JERSEY CITY, NEW JERSEY, A CORPORATION OF NEW JERSEY

UNDERGARMENT

Application filed December 11, 1930. Serial No. 501,727.

This invention relates to body garments and more particularly to a body garment in the form of a waist and hip encircling girdle for use when the person may be engaged in athletics, bathing, or other activities.

5 The primary object of the invention is to construct a body encircling girdle of the type mentioned which will automatically conform to the shape of the body, without the necessity of lacing or other fastening means, the 10 construction of the garment being such that the abdomen and waist line of the person are retained in perfect rounded outline, without undesirable protrusion of fleshy portions of the waist line and abdomen.

15 Another object of the invention is to construct a girdle of the type referred to of elastic material in such manner that the tension of the elastic material is effective in different directions upon the body so that the 20 garment will automatically assume the proper shape to act laterally about the waist and over the hips of the wearer, and will exert an upward pull upon the abdomen, thereby 25 enabling the garment to conform to the human anatomy and giving grace and form to the wearer.

Still another object of the invention is to 30 construct a garment of the above type so that the same may be formed of a single strip of elastic material which is cut in such manner that the front side portions take a lower dip than the rearward or back portion, the ends of the front side portions being connected by 35 an inelastic inverted triangular, or keystone shaped portion, whereby the angularity of the front side portions causes the inelastic portion to draw upwardly on the fleshy parts of the abdomen and thus presenting a desirable 40 flat front effect while also compressing other parts of the body such as the fleshy parts of the hips and buttocks of the wearer in desirable rounded and graceful outline.

Yet another object of the invention is to 45 provide a novel method of cutting the elastic webbing and arranging the same to produce the results already mentioned.

Still another object of the invention is to 50 equip a garment of the above character with a rearward flap portion formed of elastic

material in which the tension is normally in a horizontal direction, but which when applied to the rear of the buttocks will draw the fleshy parts together in such manner as to produce a desirable appearance, the rearward flap portion and the inelastic front insert being adapted to cooperate with a removable crotch strap, which removable crotch strap is also adapted to perform an additional function of supporting a catamenial napkin or the like.

Other objects and advantages of the invention will be hereinafter specifically pointed out, or will become apparent, as the specification proceeds.

With the above indicated objects in view, the invention resides in certain novel constructions and combinations and arrangement of parts, clearly described in the following specification and fully illustrated in the accompanying drawings, which latter show embodiments of the invention as at present preferred.

In said drawings:

Fig. 1 is a view of the present girdle in front elevation;

Fig. 2 is a rear elevation of the same;

Fig. 3 is a side elevation; and

Fig. 4 is a detail diagrammatic view illustrating the manner of cutting and forming the garment.

Referring more particularly to the drawings the girdle in this instance is formed from an elongated strip of elastic webbing 10 which is desirably of such suitable width that when the same is formed into the garment as hereinafter described, the elastic band 10 may extend partly above and partly below the waist line.

To enable the garment to exert tension upon the body both horizontally and in upwardly inclined directions at the front of the body, the front ends 11 and 12 of the band are turned inwardly and downwardly at angles designed to conform to the vertical line of the hips of the wearer as seen at 13 and 14. The end portions 11 and 12 are then cut on the bias in a direction opposite to the hip lines 13 and 14, as indicated at 15 and 16 respectively. Thus downwardly

inclined front sections 11 and 12 are then joined by means of a keystone-shaped inelastic insert 17, the sides of the insert 17 being stitched to the bias edges 15 and 16 of 5 the downwardly inclined front side members 11 and 12 respectively.

It will be seen that the side portions of the inelastic insert 17 are of greater extent than the normal width of the band 10, so 10 that the combined effect of the inclined front side portions 11 and 12 with the inelastic insert 17 will be to position the front inelastic insert 17 at a lower level upon the abdomen than the rearward part or back 18. 15 The band 10 is preferably reinforced at the center of the back of the garment by means of a vertically extending inelastic strip 19 stitched to the inner side of the band, to prevent wrinkling of the band at the rear. 20 Extending downwardly at the center of the rear of the band 10 I provide a flap portion 20 which is stitched to the bottom edge of the band portion 18, as indicated at 20', preferably formed of elastic material similar to 25 that of the band 10, with the lines of tension extending normally horizontally. This flap 20 is of downwardly tapering contour and extends downwardly to a point just above the crotch of the wearer. A crotch strap 21 30 is provided to join the lower end of the flap 20 with the lower end of the inelastic front insert 17, and this crotch strap 21 is preferably secured in place by means of removable fastening devices, such as hooks and eyes 22 35 applied to the binding edges of the strap 21 and flap 20 at the rear of the garment as seen at 23 and 24 respectively, and to the binding edges 25 and 26 of the strap 21 and front inelastic insert 17, as seen at 25 and 26 40 respectively.

When the garment is placed about the waist of the user, which is done by slipping the same upward over the hips, it is found that the rearward part of the band 10 will 45 exert tension in a horizontal direction, while the side front portions 11 and 12 will exert tension in an upward direction from the front toward the rear of the body, as seen by the arrows in Fig. 4, thus drawing the fleshy 50 parts of the abdomen upwardly, and inwardly, while also maintaining the desirable flat front effect due to the inelastic nature of the front insert 17. Even pressure 55 is imparted to the body parts throughout, so that a very smooth and rounded appearance is maintained. The inelastic insert may be of any suitable material, and may even be made of inflexible material if desired.

60 An important feature of the rearward extension or flap 20 is that while the elastic tension extends normally transversely of the flap, the flap 20 will, when the garment is in position on the body, exert pressure in various directions, thereby drawing the fleshy

parts of the buttocks downwardly, while at the same time compressing the same.

The ready detachability of the crotch strap 21, which may be formed of any suitable fabric material renders the same capable of 70 being removed and laundered, without rendering it necessary to launder the balance of the garment.

The present garment, when worn under a bathing suit, for instance, retains the abdomen and waist line in a desirable and becoming manner. The elasticity and non-elasticity of the materials used, and the manner in which the garment is cut, prevents protrusion of fatty portions of the waist line and abdomen. The presence of the garment is not observable, and the same acts as an aid to more perfect form and thus contributes toward the wearer's sense of modesty as well as comfort. 80

Considerable particularities of description, as to materials, part details, dimensions, capacities and utilities may have been herein indulged in, but it will be understood that these statements, made with particular reference to that one, and the one now preferred, of the many possible embodiments of the invention which is illustrated in the drawings, are not in any way to be taken as definitive or limitative of the invention. Inasmuch as 90 many changes could be made in the above constructions, and many apparently widely different embodiments of the invention could be made without departing from the scope thereof, it is intended that all matter contained in the above description or shown in the accompanying drawings shall be interpreted as illustrative and not in a limiting sense. 95

It is also to be understood that the language contained in the following claims is intended to cover all the generic and specific features of the invention herein described, and all statements of the scope of the invention which, as a matter of language, might be 100 said to fall therebetween.

In other words, the scope of protection contemplated is to be taken solely from the appended claims, interpreted as broadly as is consistent with the prior art. 110

What I claim is:

1. An elastic body garment including a body encircling band formed of an elongated strip of elastic material including a back portion and a pair of front side portions, 120 said front side portions being inclined downwardly toward the front of the body, the ends of said front side portions converging downwardly, an inelastic insert joined to said ends at the front of the body, said insert having downwardly tapering sides, with a top edge wider than its bottom edge, whereby said insert assumes a position on the body at a lower level than the back portion of said band, a 125 downwardly tapering elastic flap secured to 130

- the lower part of the back of said band, said flap normally having lines of tension parallel with the lines of tension of the back portion of said band and extending downwardly to a point just above the crotch of the wearer, and a crotch strap having opposite ends removably joined to the lower part of said flap and to the lower part of said front inelastic insert.
- 10 2. An elastic body garment including a body encircling band formed of an elongated strip of elastic material including a back portion and a pair of front side portions, each of said front side portions being inclined downwardly toward the lower part of the front of the body beginning at a point at about the vertical line of the hips of the wearer, the ends of said front side portions being arranged diagonally in upwardly diverging directions opposite to said inclined lines, a flexible inelastic insert joined to said ends at the front of the body, said insert having downwardly tapering sides, with a top edge wider than its bottom edge, whereby said insert assumes a position on the body at a lower level than the back portion of said band, a vertical inelastic reinforcement at the center of the back of said band, an elastic flap secured to the lower part of the back of said band, said flap normally having lines of tension parallel with the lines of tension of the back portion of said band and extending downwardly to a point just above the crotch of the wearer, and a crotch strap having opposite ends removably joined to the lower part of said flap and to the lower part of said front inelastic insert.

In testimony whereof I hereby affix my signature.

40 BENJAMIN J. COHON.
